UNITED STATES PATENT OFFICE.

CHARLES W. SHEVLIN, OF CHICAGO, ILLINOIS.

CONTAINER.

1,106,005.

Specification of Letters Patent.

Patented Aug. 4, 1914.

Application filed September 3, 1912, Serial No. 718,175. Renewed March 30, 1914. Serial No. 828,389.

To all whom it may concern:

Be it known that I, CHARLES W. SHEVLIN, a citizen of the United States, and a resident of Chicago, in the county of Cook and State of Illinois, have invented a new and useful Container, of which the following is a specification.

My present invention has relation to the variety of container the material of which may be impregnated with suitable material to provide a package for holding liquids or other commodities.

It is well known that the impregnation of the materials from which packages are made involves divers problems, and that when they are impregnated with certain material, such as paraffin, the strength and rigidity of the material of which the package is made is materially decreased. The presence also of the impregnating material sometimes interferes with the use to which the container is to be put, for instance, a container which is impregnated with paraffin easily accumulates dust, and, therefore, is unsuitable for containing commodities which are to be exhibited for sale on the shelves of a store.

My present invention has for its objects the provision of a container which will embody the advantages to be derived from impregnating the material of the same and will avoid the weakening which is usually incident to impregnation, and which can be more economically manufactured.

I attain the above objects by the structure illustrated in the accompanying drawing, in which:—

Figure 1 is a central section through a completed container; Fig. 2 is a perspective of the outer casing of the container temporarily held in shape by staples; Fig. 3 is a view similar to Fig. 2 in which the outer container is temporarily held by stitching; and Fig. 4 is a roll of impregnated liner for my package rolled up ready to be inserted in the outer casing.

Similar reference numerals designate similar parts in the several views.

The reference numeral 1 designates an outer casing which is preferably made of paper or paper board from a blank formed into a cylinder the meeting edges of which are secured together by either wire staples 2, as shown in Fig. 2, or by a row of stitching 3, as shown in Fig. 3. A suitable piece of lining paper, 4, is next provided. This is

impregnated with paraffin, or glue or cementitious impregnating material suitable for the use to which the package is to be put, which will cause the meeting surfaces of the lining to adhere together and the sides of the entire lining to adhere closely to the casing. The lining, after it has been impregnated, is then rolled up and inserted into the outer casing when, by reason of its own elasticity, it will tend to expand and contact with the walls of the outer casing. This tendency, however, should be supplemented by a suitable former which will secure a uniform and perfect contact between the liner 4 and the casing 1. When paraffin is used for impregnating, the container should be heated after the liner is in position within and in contact with the outer casing so that the paraffin will be melted and the liner and outer casing will be caused to adhere by reason of the thin film of paraffin formed by the heat between the lining and the outer casing. When glue is used the container must be dried after the lining is in position.

A closure for the bottom is next provided comprising the disk 5, to fill the bore of the casing, with the right angle flange 6 to contact with the wall thereof. A similar shaped piece having the center removed therefrom so as to provide a flange 7 to contact with the walls and an inwardly extending ridge 8, is provided for the other end so that a disk 10 may be inserted therein to form a closure for the package.

It will be seen that by this structure the outer casing of the container may be only slightly if at all impregnated, while at the same time, by reason of the impregnation of the lining, all the advantages of a package of impregnated material are secured, that is, the package may be rendered dust-proof, water-proof, dampness-proof, while at the same time the outside thereof will retain its original strength and be suitable for any purpose for which a container of ordinary paper may be used.

Having described my invention what I claim as new and desire to secure by Letters Patent, is:—

1. A container comprising an outer casing of paper or paper board, and a fibrous lining the fiber of which is completely and homogeneously infused and impregnated with paraffin wax, said lining being within said casing and contacting therewith and

adhering thereto throughout its entire extent.

2. A container comprising an outer casing of paper or paper board, and a fibrous lining the fiber of which is completely and homogeneously infused and impregnated with paraffin wax, said lining being within said casing and contacting therewith and adhering thereto throughout its entire extent, and a closure for the bottom thereof comprising a disk having an annular right angle flange adapted to assemble with the

walls of said package, and a closure for the top thereof comprising a ring having an annular right angle flange adapted to assemble with the walls of said casing, and a disk adapted to fit within the right angle flange of said ring.

In testimony whereof I affix my signature in the presence of two witnesses.

CHARLES W. SHEVLIN.
